UNITED STATES PATENT OFFICE.

KARL LEISSE AND FRANK BACH, OF CHICAGO, ILLINOIS

WRENCH.

1,108,591.

Specification of Letters Patent. Patented Aug. 25, 1914.

Application filed April 16, 1914. Serial No. 832,269.

To all whom it may concern:

Be it known that we, KARL LEISSE and FRANK BACH, respectively a subject of the Emperor of Germany and a citizen of the 5 United States, both residing at Chicago, in the county of Cook and State of Illinois, have invented certain new and useful Improvements in Wrenches, of which the following is a specification.

10 Our invention relates to wrenches or spanners and has especial reference to that class of tools in which the jaws are relatively adjustable as in such tools commonly known as monkey wrenches.

15 One of the general objects of our invention is to provide an improved spanner tool, having an adjustable jaw, as used in wrenches for engaging round objects, such as pipes, or the like, and are commonly 20 known as pipe wrenches, and with slight modifications, without changing the character of our invention, adapted for engaging angular objects, such as bolt heads and nuts and wherein the adjustable jaw may quickly 25 be moved to selected position to engage an object and automatically lock itself in place against displacement due to stress that may be applied to the jaws during the operation of turning the object.

30 Another, and more specific object, of our invention is to provide a clamping means, in addition to the jaw locking means, adapted and arranged to move the adjustable jaw slightly closer to the fixed jaw, after 35 locking the latter against retraction, and thereby grasp and hold the intermediate object firmly between the jaws, so that it will not fall from them when not otherwise supported.

40 Other and further objects of our invention will be readily understood from a consideration of the following description when taken in conjunction with the drawing, wherein—

45 Figure 1 is a side elevation of the wrench. Fig. 2 shows the wrench turned to an angle of 90 degrees and showing an edge elevation thereof. Fig. 3 shows a side elevation after the clamping eccentric has been moved to 50 push the jaws closer together to clamp the object that may be contained between the jaws, as will be hereinafter explained. Fig. 4 is a fragment of the wrench, showing parts in sections. Fig. 5 is a transverse section, 55 taken on line 5—5 of Fig. 4. Fig. 6 is a ratchet pawl for locking the movable jaw

to the shank of the wrench. Fig. 7 is a bushing and spacing sleeve for the movable eccentric and Fig. 8 is a movable eccentric adapted to be used for moving the adjustable jaw into closer relation with the fixed jaw to clamp the object.

In all the views the same reference characters are employed to indicate similar parts.

10 is the handle, or shank of the wrench, carrying on its forward end a fixed jaw 11 and provided with ratchet teeth on its inner edge 12. The movable jaw 13 is freely slidable upon the shank, or handle 10. A spring 14 is provided with one or more ratchet teeth 15, that are adapted to engage the teeth 12 of the handle 10, and it is furthermore provided with a thumb piece extension 16, counterbored as at 17, to accommodate an open helical spring 18, that has bearing against a portion of the jaw, as at 19, to normally hold the teeth 15 of the pawl in contact with the ratchet teeth 12. The ratchet pawl 14 is bored large, as at 20, 70 for insertion of the clamping eccentric 21, which has bearing on the pin 22 that passes through the lower portion 23 of the jaw 13. A wearing thimble 24, may be inserted between the pin 22 and the eccentric 21. It 75 acts as a spacing means for maintaining the parts 23—23 of the jaw 13 properly spaced apart and may be renewed in case of wear to prevent the necessity of renewing the more expensive eccentric 21. The eccentric 90 21 is carried on a knurled lever 25 which may be, and preferably is, an integral part thereof.

The operation of the device is as follows:—When an object is inserted between 95 the jaws 11 and 13, the latter may be shoved up against the object and it will be automatically locked in this position, by the pawl 14, the teeth of which engage the ratchet teeth 12 of the handle 10, the pawl 100 being yieldingly held in this position by the spring 18. This will lock the movable jaw against retraction or displacement. After this is done the tool may be used as an ordinary wrench and the adjustable jaw 13 will 105 not be displaced by the stress that may be exerted due to the effort of turning the object that is contained between the jaws. If it is desired to hold the object tightly between the jaws, such as a nut, or the like, so 110 that it will not drop from the jaws, the eccentric lever 25 is moved from the position

shown in Fig. 1 to approximately the position shown in Fig. 3, at which time the heavier part of the eccentric 21 will bear against the short end of the ratchet pawl 14 and will thus move the jaw 13 a slight distance nearer and toward the fixed jaw 11, thereby clamping the object that may be contained between the jaws, firmly and securely holding it in place.

- 10 The jaw 13 may be freely moved on the shank or handle 10, at any time, back and forth by placing the thumb upon the end 16 of the ratchet lever and depressing it against the resiliency of the spring 18, thereby lifting the ratchet teeth 15 from the ratchet 12. By this means the jaw 13 may be quickly brought up against the object, contained between the jaws, after which the jaws may be made to firmly clasp the object by moving the eccentric lever 25 from the position shown in Fig. 1 toward the position shown in Fig. 3. The movement of the lever 25, to the latter position, pushes the jaw 13 forward a distance, in practice equal to about 15 $\frac{3}{8}$ of an inch, or the width of one tooth which is sufficient to cause firm and unyielding contact to be made with the object, such as a nut or the like, so that the tool may be used freely without causing the nut 20 to fall therefrom. When the tool is properly designed for a pipe wrench it may be made to grasp and hold a small piece of pipe, a nipple or the like, in a similar manner.
- 25 30 While we have herein shown a single embodiment of our invention for the purpose

of clear disclosure it is evident that changes may be made therein within the scope of the appended claims.

Having described our invention, what we claim is:—

1. A wrench, comprising a shank and a jaw affixed to one end thereof; ratchet teeth, formed upon one side of the shank; a second jaw, slideable upon said shank; an eccentric, 45 rotatably secured at its axis in the slideable jaw; a pawl, journaled upon said eccentric and adapted to engage said ratchet teeth; a thumb piece, projecting from said pawl, and resilient means for normally holding said pawl in engagement with the ratchet teeth.

2. A wrench, comprising a shank and a jaw affixed to one end thereof; ratchet teeth, formed upon one side of the shank; a second jaw, slideable upon said shank; an eccentric, 55 rotatably secured at its axis in the slideable jaw; a pawl, journaled upon said eccentric and having a projection at one side adapted to engage said ratchet teeth; a thumb piece, projecting from said pawl at the side opposite to that which engages with the ratchet teeth, and an open helical spring interposed between said thumb piece and said movable jaw substantially as and for the purpose set forth.

60 In testimony whereof we hereunto set our hands.

KARL LEISSLE.
FRANK BACH.
